UNITED STATES PATENT OFFICE.

HUGO M. KUNIOLM, OF GARDNER, MASSACHUSETTS, ASSIGNOR TO HEYWOOD-WAKEFIELD COMPANY, OF GARDNER, MASSACHUSETTS, A CORPORATION OF MASSACHUSETTS.

METHOD OF AND APPARATUS FOR ASSEMBLING WIRE WHEELS.

Application filed October 27, 1923. Serial No. 671,184.

To all whom it may concern:

Be it known that I, HUGO M. KUNIOLM, a citizen of the United States, residing at Gardner, in the county of Worcester and 5 State of Massachusetts, have invented a new and useful Method of and Apparatus for Assembling Wire Wheels, of which the following is a specification.

This invention relates to the assembling 10 or hanging of a wire wheel, that is, the insertion of the ends of the wire spokes into perforations through the metal rim and the swaging of the outer ends of the spokes so as to hold them in that position. The 15 threading of the spokes into the rim is done by hand at the present time and is a very slow process. Each wheel comprises a previously formed metal rim having equally spaced perforations for the spokes. A central hub is provided with circular flanges at 20 its ends spaced apart and two sets of spokes. Half the spokes are connected with one of the circular flanges and the other half with the other and the two sets of spokes are so 25 arranged that they are out of registration with each other. For example, if there are four spokes on each side as indicated in the drawings, each spoke makes an angle of 45° with the two adjacent spokes of the other 30 set.

This invention relates to the production of practically the same wheel, no changes being made in the wheel itself except that the spokes are nail pointed before they are 35 assembled and swaged over at the ends. The object of the invention of course is to facilitate the operation of assembling or hanging the wheel and to save greatly in labor cost and secure accurate and uniform 40 results.

Reference is to be had to the accompanying drawings, in which—

Fig. 1 is a diametrical sectional view of 45 a set of dies for hanging a wheel in accordance with this invention showing the parts of the wheel located therein and the dies separated;

Fig. 2 is a similar view showing the dies brought together so that the wheel is completely assembled;

Fig. 3 is a plan of the bottom die with the parts in the position shown in Fig. 1; and

Fig. 4 is a diametrical sectional view on the line 4—4 of Fig. 3 to illustrate the upper set of spokes in position with the dies open. 55

Referring first to Fig. 1, it will be seen that I have shown two main dies 10 and 11. Each of these dies has a central perforation in which is a centering pin 12 fixedly located. The dies also have spoke guides 13 60 and 14 respectively. These guides may be of any form but I have shown them as bifurcated and having vertical radial passages in them fitting the spokes S and guiding them in a vertical direction, that is, 65 keeping them from moving around the wheel in any way. The ends of the guides are slanted at the desired angle of the spokes in the completed wheel.

These features constitute the main elements of the two dies but around each die I have provided a ledge 15 for positively limiting the motion of an annular ring 16. This annular ring on the lower die is supported by a series of springs 17 equally spaced apart and a corresponding series of springs are located on the upper die to hold the upper ring down with a yielding pressure. When the dies come together these rings are pressed back on the ledges 15 70 against the force of the springs and therefore they are registered properly with respect to the main dies as shown in Fig. 2. These rings are also provided with guide studs or screws 18 having heads reciprocable in passages 19 in the back side of each of the respective dies. This limits the motion of the rings away from the dies, caused by the springs, and this limitation is accurate so that when the dies are open the 80 rings are always projected the same distance. 85

Each ring is provided with a groove 20 in the face. These two grooves register with each other and constitute a locating means 95 for the wheel rim R. Also located on the lower ring 16 is a block 22 held on the ring by screws 23 or the like and provided with a rim hole locating pin 24 slidable in the block and having an end adapted to project 100 into the space between the two rings 16 and into a spoke hole in the wheel rim R held therein.

The work which is to be put in these dies

- comprises as stated, a central hub H preferably of sheet metal and having been formed in cylindrical shape with a pair of beads near the ends which are open.
- 5 Around this hub at one end is a circular sheet metal flange F previously centered on the bead and secured thereto. It is flanged over at its edge to provide inwardly projecting flanges having spaces between them.
- 10 These flanges extend over and pinch a piece of wire extending circumferentially and forming a part of two adjacent spokes S as is usual in this industry. It will be seen therefore that every alternate one of these
- 15 flanges has secured under it this portion of wire so as to hold the two adjacent spokes which constitute the ends of this piece of wire and project from it radially and also at a uniform inclination, as indicated in Fig. 1.
- 20 The spokes are bent or dished farther out of the plane of the flange than they will be when the wheel is finished. The ends of these spokes are nail pointed.

In the lower groove 20 I locate the previously formed rim R. This rim is shaped up outside of this machine and provided with eight perforations if there are eight spokes, these perforations being equally spaced. The groove is of a size and shape to support this rim accurately in position and the rings 20 are either beveled off or transversely grooved so that the ends of the spokes can rest as shown in Fig. 1 in position to register with the holes in the rim and enter them 35 when the two dies are pressed together.

In this description I have ignored the upper die 11. That is not in place while the parts above described are being located. The upper set of spokes S, attached to a circular flange F but entirely separate from the hub, is now placed in position. The nail pointed ends of the spokes are placed in depressions in the rim 16. This is all that is necessary to properly locate this upper set 45 of spokes. These spokes, it will be understood, alternate with the lower spokes so that if there are eight spokes in the wheel there are four in each set and those of each set make an angle of 45° with the adjacent ones of the other set. This principle is maintained if the number of spokes is larger.

The parts are so arranged that the guides 13 and 14 accurately maintain the spokes in 55 these relative positions and when the die 11 is brought down and forced toward the die 10 against the action of the several springs the two sets of spokes will be flattened out to some extent that is, until they come against 60 the bottoms of the guides in the grooves 13 and 14 which bottoms are slanted as clearly shown. This also causes the two rings 16 to be seated finally back on the ledges 15 where positive pressure is applied to them 65 from that point. At the same time the

pointed ends of all the spokes project through their respective perforations in the rim. The force applied in performing this action results in flattening out the two sets of spokes to an equal extent so that they 70 are still dished just the amount required for the complete wheel. The upper flange is forced on the upper bead of the hub by the same motion and both ends of the hub are flared outwardly at the ends on account of 75 the tapering shoulders 32 on the pins 12. This operation can be performed separately if desired. At the same time one spoke pushes out the pin 24 which is tapered on the end to a near point so, when the wheel 80 is ejected, it will slide way out.

This provides a purely mechanical method of hanging the wheel as it is not even necessary to adjust the ends of the spokes to the holes in the rim. They simply have to be inserted 85 in the guides and the rim also has to be placed in proper position with respect to the pin 24. This registers all the parts so that they will come into proper position when the pressure is applied. When the pressure 90 is removed and the upper die lifted the springs force the lower ring 16 upwardly to the position shown in Fig. 1 and take with it the whole wheel which is supported thereby. The movement is far enough to free 95 the hub from the lower pin 12 and eject the wheel. The ends of the spokes are swaged over afterwards. As everything is done in dies all the wheels come through in uniform shape and the labor cost is very greatly reduced.

Although I have illustrated and described only a single form of the invention I am aware of the fact that modifications can be made therein by any person skilled in the art without departing from the scope of the invention as expressed in the claims.

Therefore I do not wish to be limited to all the details of construction herein shown and described but what I do claim is:—

1. In a wheel assembling device, the combination of a pair of dies having means for registering and guiding the spokes, with a ring connected with one die and surrounding it and provided with means for receiving and holding in proper position the rim of the wheel, and means whereby when the dies are forced together the spokes will be forced into holes in the rim and pushed through the same.

2. In a wheel assembling device, the combination with a die, having a radial set of guides for guiding the spokes of a wheel, of means for supporting a rim previously perforated, said parts being so arranged that when pressure is applied the several spokes will enter the perforations in the rim.

3. In a wheel assembling device, the combination with a pair of dies, each having radial sets of guides for guiding half the

spokes of a wheel, of means at the edges of said dies for supporting a rim previously perforated, said parts being so arranged that when the dies are forced together the several 5 spokes of the two sets will enter a single series of perforations in the rim, said guides being rigidly arranged and having rear surfaces arranged at equal angles to the central plane of the wheel, whereby when the spokes 10 are forced outwardly at their ends they will come to a uniform angle to the plane of the wheel.

4. In a wheel assembling device, the combination of a pair of dies, each having means 15 for registering and guiding one set of spokes, and a central pin for centering part of the hub of the wheel and thereby centering the spokes connected therewith, with a ring connected with each die and surrounding it and 20 provided with means for receiving and holding in proper position the rim of the wheel, and means whereby when the dies are forced together the spokes held by them will be forced into holes in the rim and pushed 25 through the same.

5. In a wheel assembling device, the combination of a pair of dies, each having means for registering and guiding one set of spokes, with a ring connected with each die and 30 surrounding it and provided with means for receiving and holding in proper position the rim of the wheel, yielding means for supporting said rings from their respective dies, each die having a ledge against which its 35 ring is adapted to be forced when the dies are forced together to form a positive seat and locate the rim at a definite elevation when the assembling operation is finished, and means whereby when the dies are forced 40 together the spokes held by them will be forced into holes in the rim and pushed through the same.

6. In a wheel assembling device, the combination of a pair of dies, each having means 45 for registering and guiding one set of spokes, with a ring connected with each die and surrounding it and provided with means for receiving and holding in proper position the rim of the wheel, yielding means for supporting said rings from their respective dies, each die having a ledge against which its 50 ring is adapted to be forced when the dies are forced together to form a positive seat and locate the rim at a definite elevation 55 when the assembling operation is finished, means whereby when the dies are forced together the spokes held by them will be forced into holes in the rim and pushed through the same, and an opposite series of 60 guide pin studs having means for limiting the movement of the rings away from the dies by the action of its springs.

7. In a wheel assembling device, the combination with a lower and an upper die each 65 having radial sets of guides for guiding half

the spokes of a wheel, means at the edges of said dies for supporting a rim previously perforated, one of said rings being provided with a block mounted thereon and a pin supported by said block and adjustable into a 70 position to register the perforations of the wheel rim to receive the ends of the spokes.

8. The method of assembling wire wheels which consists in mounting a tubular hub having a circular flange, supporting half of 75 the wire spokes of the wheel on a center, centering the other half of the spokes in registration therewith, locating a rim previously perforated for the reception of the spokes at a point adjacent to the ends of 80 the spokes and then forcing the two sets of spokes toward each other to cause them to enter the perforations in the rim, and the two centers to come closer together.

9. The method of assembling a wire wheel which consists in mounting a flange on one end of a tubular hub, said flange having one set of spokes mounted thereon, dishing these spokes at a sharper angle than they will have in the completed wheel, centering 85 the other set of spokes mounted on a similar flange at a point opposite the first spokes, providing the spokes with nail points, locating a previously formed rim having perforations at regular intervals in such position 90 that each perforation registers with the pointed end of one of the spokes and is closely adjacent thereto, forcing the two sets of spokes toward each other, and guiding the ends of the spokes into their respective perforations, whereby the two sets of spokes are 95 flattened out partly but left in a properly dished condition.

10. The method of assembling a wire wheel which consists in mounting a flange 100 on one end of a tubular hub, said flange having one set of spokes mounted thereon, dishing these spokes at a sharper angle than they will have in the completed wheel, centering the other set of spokes mounted on 105 a similar flange having a central perforation at a point opposite the hub, providing the spokes with nail points, locating a previously formed rim having perforations at regular intervals in such position that each perforation registers with the pointed end of 110 one of the spokes and is closely adjacent thereto, forcing the two sets of spokes toward each other and guiding the ends of the spokes into their respective perforations, whereby the two sets of spokes are flattened out partly but left in a properly dished condition, and the second flange is forced over 115 and fixed to the other end of the hub.

11. The method of assembling wire wheels which consists in mounting a tubular hub supporting half of the wire spokes of the wheel on a center, centering the other half of the spokes in registration therewith, locating a rim previously perforated for the 120 125 130

reception of the spokes at a point adjacent and provided with a flaring shoulder for to the ends of the spokes and then forcing swedging out the end of the hub, with a 15 the two sets of spokes toward each other to bring connected with each die and surround cause them to enter the perforations in the ring it and provided with means for receiving the rim, and the two centers to come closer to bring and holding in proper position the rim together, and simultaneously swedging out of the wheel, and means whereby when the 20 wardly the open ends of the hub. dies are forced together the spokes held by

12. In a wheel assembling device, the combination of a pair of dies, each having them will be forced into holes in the rim and pushed through the same. 10 means for registering and guiding one set. In testimony whereof I have hereunto of spokes, and a central pin for centering affixed my signature. part of the hub of the wheel and thereby centering the spokes connected therewith,

HUGO M. KUNIHLOM.
